UNITED STATES PATENT OFFICE.

FRED A. SCHWARTZ, OF BROOKLYN, NEW YORK.

AUTOMATICALLY-ADJUSTABLE KNIVES FOR USE WITH RUBBER-WORKING CALENDERS.

1,381,242.

Specification of Letters Patent. Patented June 14, 1921.

Application filed February 10, 1921. Serial No. 443,916.

To all whom it may concern:

Be it known that I, FRED A. SCHWARTZ, a citizen of the United States of America, residing in the city of Brooklyn and State 5 of New York, have invented new and useful Improvements in Automatically-Adjustable Knives for Use with Rubber-Working Calenders, of which the following is a specification.

10 The invention relates to an improved apparatus that is adapted more particularly to provide a simple, efficient, and automatically operated device of this character with which fabric or cord, such as is employed in the construction of casings for 15 pneumatic tire tubes, may be expeditiously and economically "frictioned."

Frictioned as the term is employed in this specification is the process of applying rubber compound to the surface of the surface 20 of the fabric or cord referred to in the foregoing paragraph.

The process of frictioning the fabric is accomplished by passing the rubber compound 25 between the two upper of three revolving cylinders that are positioned on the same vertical plane, and causing the rubber compound to be applied to the upper surface of the fabric or cord that is caused to pass between the two lower of the three revolving 30 cylinders.

It will be readily comprehended, that to accomplish this process in an efficient and accurate manner, it is necessary that the 35 width of calendered rubber compound that is lifted from the surface of the central calendering cylinder, and thus transferred to the fabric or cord, be precisely the same in width as the fabric or cord. Also it is 40 highly important, that the desired width of rubber compound be separated from the surplus width carried by the central revolving cylinder, so as to aline the edges of the width of rubber compound with the edges of 45 the fabric or cord.

In order to secure the best results it is common practice to regulate the movement of the knives by manual labor, thereby requiring the service of two persons that 50 manipulate the knives which contact with the surface of the central revolving cylinder; the function of the knives being to separate the surplus rubber compound from the desired width that is to be transferred 55 to the surface of the fabric or cord by the

pressure exerted upon the fabric by the revolving calendering cylinders.

With my invention in use, better and more accurate results are obtainable, and without the aid of expensive manual labor.

With this object in view, the invention consists in the novel construction, and combination of parts as hereinafter described, illustrated in the accompanying drawings, and particularly pointed out in the appended claims.

Referring to the drawings forming a part of this specification, Figure 1 is a vertical cross section of a rubber working calender, illustrating the direction of revolution of 70 the calendering cylinders, and the relative position of the parts that control the movement of the fabric or cord.

Fig. 2 is a top view of the improved apparatus.

Fig. 3 is a side view of one of two similar knives supporting members, and a fragmentary cross section of the central calendering cylinder, illustrating the method of 80 contacting the knives and the surface of the cylinder.

Fig. 4 is a horizontal section of a grooved collar that is mounted upon a hollow cylinder or sleeve, which receives and is supported by a length of shafting; also a sectional fragment of the horizontal length of 85 the hollow cylinder and shafting therein.

Fig. 5 is an edge, and Fig. 6 a side view of the slotted collar.

The operation of my improved apparatus is as follows:—Referring to Fig. 1, the numerals 1, 2, and 3 indicate the calendering cylinders of the calender. The fabric that is in proper position to be frictioned is indicated by the numeral 4. The arrows 5, 95 5, 5, indicate the direction of the revolution of the calendering cylinders 1, 2, 3, and the arrows 6, 6, the direction in which the fabric is caused to pass between the cylinders.

That the simplicity of adaption to its intended use of my improved apparatus may be more readily comprehended, it may be remarked, that to properly and conveniently manipulate the fabric or cord while it is being calendered, all calenders intended for this purpose are equipped with horizontal rollers, as indicated by the reference numbers 7 and 8. Thus, it will be noted that it is not necessary to remove a part of the regular equipment in order to employ my im- 110

proved apparatus, as the apparatus as described in this specification coöperates with, but does not take the place of the regular equipment.

- 5 Referring to the roller (or shafting) 8, the function of which is to support and aline the fabric with the horizontal surfaces of the calendering cylinders 2 and 3, in the improved equipment the length of shafting 10 8 is placed within a hollow cylinder or sleeve 9. With the parts so arranged, the hollow cylinder or sleeve necessarily supports the fabric or cord as it is being advanced by the revolving calendering cylinders 15 2 and 3. The hollow cylinder 9 carries the slotted collars 10, 10, which may be adjusted and secured at any desired position upon the length of the hollow cylinder by causing the thumb screws 12 and 13, to contact with the 20 surface of the hollow cylinder.
- In Fig. 3 is illustrated the means I prefer to employ to secure the proper contact of the knives upon the surface of the calendering cylinder.
- 25 The hollow stem 14, which receives the stem 15, to which the cutting knives 16 are attached, terminates in a fork 17 that is adapted to engage the circumferentially directed groove 18 in the collar 10 that is 30 carried by the hollow cylinder 9 which is supported by, and revolves with, or upon the length of shafting 8. The stem 15 having free movement within the hollow stem 14 may be adjusted so as to contact the cutting 35 knives 16, and the surface of the calendering cylinder 2, as indicated. The proper tension is secured by the action of coil springs 19, and maintained by the proper adjustment of the collar 20.
- 40 The operation of the improved automatically adjustable knives is as follows:—Referring to the fabric or cord that is indicated by the numeral 4, Fig. 1, by an arrangement of friction brakes that are a part 45 of the regular equipment of the calender, the fabric when being drawn forward by the revolving calendering cylinders is kept taut. This necessarily results in there being a positive contact of the surface of the hollow cylinder and the advancing fabric by which the 50 revolution of the hollow cylinder is effected, but, as the hollow cylinder is free to revolve upon or with the shafting, the taut fabric is not resisted in its forward movement by the 55 hollow cylinder.

It is desired now to particularly direct attention to the fact, that as the fabric is unwound from the roll 21, by the revolving calendering cylinders, the advancing width 60 of fabric is inclined to pass between the horizontal surfaces of the revolving cylinders on an irregular plane.

That is by reason of irregular winding of the fabric, and various other causes, it is 65 practically impossible to advance the fabric

so as to keep the edges in alinement with knives that are supported and kept in contact with the revolving calendering cylinders by apparatus that is rigidly secured in its operative position. With my improved 70 apparatus in use, by reason of the hollow cylinder 9 having a positive contact with the taut fabric or cord, and by reason of the hollow cylinder having free play upon the shafting 8 in the direction of the horizontal 75 plane of the calendering cylinders, it follows that any irregular movement of the advancing width of fabric will shift the hollow cylinder a corresponding distance, thereby causing the cutting knives that contact with 80 the central revolving calendering cylinder to be shifted a corresponding distance upon the horizontal plane of the cylinder from which the rubber compound is lifted by the advancing fabric or cord. Thus, by the means just 85 described, the knives are automatically adjusted and kept in true alinement with the edges of the fabric or cord as it is advanced in the direction of the revolution of the cylinders.

I claim as my invention:

1. In automatically adjustable knives supporting apparatus for use with calenders that are adapted to calender rubber compounds, the combination of a hollow cylinder or sleeve that is adapted to encompass a length of shafting, the said length of shafting being extensive therefrom, and supported in horizontal position by means of suitable bearings that receive the extending 100 ends, the said bearings being secured to the vertical frame or side standards of the said calender, and so positioned as to aline the upper horizontal surface of the said hollow cylinder or sleeve with the horizontal line 105 of contact of the curved surfaces of the two lower positioned of three calendering cylinders that are positioned on the same vertical plane.

2. In automatically adjustable knives supporting apparatus for use with calenders that are adapted to calender rubber compounds, the combination of a hollow cylinder or sleeve, that is adapted to aline fabric or cord with the horizontal plane of contact of revolving calendering cylinders, a horizontal length of shafting that carries and upon which the said hollow cylinder or sleeve is caused to revolve by the forward movement of the said fabric or cord that is 115 effected by the revolution of the calendering cylinders, the momentarily positive contact of the fabric or cord functioning to transfer to the said hollow cylinder or sleeve the irregular transverse movement of the said 120 fabric or cord.

3. In automatically adjustable knives supporting apparatus for use with calenders that are adapted to calender rubber compounds, the combination of a horizontally 130

- directed length of shafting, a hollow cylinder or sleeve that is adapted to encompass the said length of shafting, grooves centrally positioned in the outer peripheries of collars that are slidably mounted upon the said hollow cylinder or sleeve, means to align and support the said shafting, and hollow stem members that terminate in forked members that are adapted to be received by the said grooves.
4. In automatically adjustable knives supporting apparatus for use with calenders that are adapted to calender rubber compounds, the combination of knives supporting members that terminate in stems that are adapted to be received by hollow stems carried by forked members which engage circumferentially directed grooves in the outer peripheries of collars that are slidably mounted and capable of being rigidly se-

cured at a determined position upon a hollow cylinder or sleeve that has free horizontal movement upon a horizontally directed length of shafting, rubber compounds cutting knives, that are carried by the said 25 knives supporting members, and coil springs that are adapted to contact the said rubber compounds cutting knives and the surface of the revolving calendering cylinder by exerting pressure upon the said forked members that is reacted by the knives supporting members to provide tension between the revolving grooved collars and the contacting knives, as substantially described.

In testimony whereof I affix my signature. 35

FRED. A. SCHWARTZ.
